(57) **CLAIM**

The ornamental design for a dental crown, as shown and described.

DESCRIPTION

FIG. 1 is a perspective view of the top of a dental crown showing the posterior of a dental crown;

FIG. 2 is a perspective view of the bottom of the posterior dental crown showing the inside of the dental crown;

FIG. 3 is a top plan view of the posterior dental crown;

FIG. 4 is a bottom plan view of the posterior dental crown showing the inside of the dental crown;

FIG. 5 is a side mesial elevational view of the posterior dental crown;

FIG. 6 is a side distal elevational view of the posterior dental crown;

FIG. 7 is a side buccal elevational view of the posterior dental crown;

FIG. 8 is a side lingual elevational view of the posterior dental crown;

FIG. 9 is a perspective view of the top of an anterior dental crown;

FIG. 10 is a perspective view of the bottom of the anterior dental crown showing the inside of the dental crown;

FIG. 11 is a top plan view of the anterior dental crown;

FIG. 12 is a bottom plan view of the anterior dental crown showing the inside of the dental crown;

FIG. 13 is a side buccal elevational view of the anterior dental crown; the side lingual elevational view being a mirror image thereof; and,

FIG. 14 is a side mesial elevational view of the anterior dental crown; the side distal view being a mirror image thereof.
